(57) **CLAIM**

The ornamental design for a connector module, as shown and described.

DESCRIPTION

FIG. 1 is a front perspective view of a connector module in accordance with the present invention;

FIG. 2 is a front view of the connector module shown in FIG. 1;

FIG. 3 is a back view of the connector module shown in FIG. 1;

FIG. 4 is a left side view of the connector module shown in FIG. 1;

FIG. 5 is a right side view of the connector module shown in FIG. 1;

FIG. 6 is a top view of the connector module shown in FIG. 1;

FIG. 7 is a bottom view of the connector module shown in FIG. 1;

FIG. 8 is a front perspective view of a top piece of the connector module shown in FIG. 1;

FIG. 9 is a front view of the top piece of the connector module shown in FIG. 1;

FIG. 10 is a back view of the top piece of the connector module shown in FIG. 1;

FIG. 11 is a left side view of the top piece of the connector module shown in FIG. 1;

FIG. 12 is a right side view of the top piece of the connector module shown in FIG. 1;

FIG. 13 is a top view of the top piece of the connector module shown in FIG. 1;

FIG. 14 is a bottom view of the top piece of the connector module shown in FIG. 1;

FIG. 15 is a front perspective view of a bottom piece of the connector module shown in FIG. 1;

FIG. 16 is a front view of the bottom piece of the connector module shown in FIG. 1;

FIG. 17 is a back view of the bottom piece of the connector module shown in FIG. 1;

(Continued)

FIG. 18 is a left side view of the bottom piece of the connector module shown in FIG. 1;
 FIG. 19 is a right side view of the bottom piece of the connector module shown in FIG. 1;
 FIG. 20 is a top view of the bottom piece of the connector module shown in FIG. 1;
 FIG. 21 is a bottom view of the bottom piece of the connector module shown in FIG. 1;
 FIG. 22 is front perspective view of the connector module shown in FIG. 1 connecting two standard Lego® blocks in accordance with the present invention;
 FIG. 23 is front perspective view of the connector module shown in FIG. 1 connecting a sensor in accordance with the present invention; and,
 FIG. 24 is front perspective view of the connector module shown in FIG. 1 connecting two standard Lego® blocks and a sensor in accordance with the present invention.
 The broken lines in the drawings illustrate portions of the connector modules that form no part of the claimed design.
